Specification for Design.

Patented Sept. 13, 1921.

Application filed January 14, 1921. Serial No. 437,363. Term of patent 14 years.

To all whom it may concern:

Be it known that I, HARRY C. ADAM, a citizen of the United States, residing at St. Louis, Missouri, have invented a certain new, original, and ornamental Design for a Lighting-Fixture Urn, of which the following is a specification, reference being had to the accompanying drawings, forming a part thereof.

Figure 1 of the drawing is a side elevational view, with the ornamentation shown in flat relief, and Fig. 2 is a bottom plan view of my new design for a lighting-fixture urn.

I claim:

The ornamental design for a lighting-fixture urn, as shown.

HARRY C. ADAM.
